(57) **CLAIM**

We claim the ornamental design for an automated teller machine storage cassette, as shown and described.

DESCRIPTION

FIG. 1 is a front right isometric view

FIG. 2 is a front elevational view.

FIG. 3 is a right side view.

FIG. 4 is a left side view; and,

FIG. 5 is a top view.

Surfaces not shown are unornamented and are not part of the claimed design.
